UNITED STATES PATENT OFFICE.

JAMES S. BRENNAN, OF ATTLEBORO, MASSACHUSETTS.

ORNAMENTAL LIGHTING STRUCTURE.

Application filed July 7, 1926. Serial No. 120,934.

This invention relates to an ornamental lighting structure which comprises ornamental holders for electric lights and means for connecting the same with an electric circuit, and which is particularly adapted for use in connection with certain religious ceremonies, such, for example, as funerals.

Since, in certain religious ceremonies it is customary to use lighted candles or tapers, and the open flame therefrom is liable to ignite draperies or the clothing of those present, I have provided a lighting structure comprising ornamental supports for electric lamps and bearing ornamentation of the character associated with such religious ceremonies, whereby the appearance of ordinary tapers may be simulated and the hazard of fire by reason of open flame entirely eliminated.

Referring to the drawings:

Fig. 1 is a perspective view of the ornamental lighting structure, wherein the lighting elements are arranged after the manner commonly employed in the conduct of funeral ceremonies.

Fig. 2 is an elevational view of one of the ornamental supports or lighting elements, and illustrating a form of ornamentation as applied thereto, and,

Fig. 3 is a vertical sectional view of the ornamental support or lighting element shown in Fig. 2.

The structure as shown in the drawings comprises stands or holders 1 which may be of any desired construction and which are each provided with an open recess for receiving the base of one of the ornamental supports or lighting elements to hold the same in upright position.

One of the ornamental supports or lighting elements 2 is carried by each of the stands 1, the base thereof fitting within the recess at top of the stand as indicated at 3.

Each of the lighting elements 2 is formed of quasi cylindrical shape and provided with a base portion 5 which fits within the recess at the top of a stand 1. The upper end portion of each member 2 is tapered as at 4 to more closely resemble the appearance of a candle, and is provided with a socket 6 within which is threaded an ornamental lamp 7 which may be so shaped as to resemble the form and appearance of an open flame. A bore 8 extends throughout a portion of the member 2, substantially centrally

thereof, and connects with a lateral opening 9 formed in the side wall of the member 2. A plug 10 is positioned in the opening 9 and is secured against accidental removal therefrom by a screw 11, the plug being provided upon its outer extremity with electrical terminals 12 and 13 of conventional form. The terminals 12 and 13 are electrically connected with the lamp socket and base by means of wires 14 and 15 which may be encased in the usual cord 16.

Upon the outer surface of the member 2 is positioned ornamental bands 17 and 18, which are spaced from each other, and a suitable ornamental plaque 19 is secured to the member 2 intermediate the bands 17 and 18.

When positioned in the stands or holders 1, the members 2 are connected to a source of electric current 20 by a main cord 21, multiple connector 22 and individual cords 23 which carry connections 24 adapted to be removably connected to the terminals 12 and 13 to conduct the electric current to the lamps 6 through the wires 14 and 15.

The ornamental structure shown provides a portable and ornamental lighting structure capable of being quickly and easily assembled or disassembled, and which simulates the appearance of ordinary tapers, while obviating entirely the fire hazard due to the use of ordinary candles or tapers.

What I claim is:

In an ornamental lighting structure, a support formed to simulate the appearance of a taper and provided with a central longitudinal bore extending throughout a portion only of its length, a lamp base secured to said support adjacent to one end of said bore, an electric lamp carried by said base, ornamental bands surrounding said support and secured thereto, a lateral opening formed in the wall of said support intermediate the ends thereof and communicating with the central bore, a plug removably secured in said lateral opening and serving as a closure therefor, said plug being provided with electric terminals, means within the bore for connecting the terminals of said plug with the lamp base, and a removable connection for connecting said terminals with an electric circuit.

In testimony whereof I have affixed my signature.

JAMES S. BRENNAN.
